William L. Washburn, of Springfield, Mass.
Letters Patent No 1654, dated Sept. 2, 1862,

The schedule referred to in these Letters Patent and making part of the same.

To all whom it may concern:

Be it known that I, William L. Washburn, of Springfield in the County of Hampden, and Commonwealth of Massachusetts, have invented or produced a new and original design for a Burial Case, and I do hereby declare that the following is a full and exact description of the same, reference being had to the accompanying drawings, in which

Fig. 1, is a side elevation,

Fig. 2, a plan or top view,

Fig. 3, an elevation of the head,

Fig. 4, an end elevation at the foot, and

Fig. 5, a cross section.

Like letters of reference indicate corresponding parts in each of the several figures.

The design for which I desire to secure letters patent consists of a Burial Case, Basket or Coffin, constructed

2

Des. 1654

as follows - The general form is such that the top, side and end views show a trapezoidal form as seen in drawings.

This general form is varied and ornamented by forming the recessed circular corners a. a. a. a. at each of the four corners of the case, both in the case proper and in the cover, which projects over the walls on the sides and ends.

In the walls I form the recessed panels b. b. b. and on the cover the raised panels c. c. surrounded by the mouldings d. broken round the corners to correspond to the corner of the cover, which cover has a moulding worked round its edge.

Now what I claim as new and desire to secure by Letters Patent, is.

The burial case, having the form herein described and illustrated in the drawings when ornamented by the corners a. a. a. a. panels b. b. b. and c. c. and moulding d.
